UNITED STATES PATENT OFFICE.

OTTO SPAHR, OF PHILADELPHIA, PENNSYLVANIA, ASSIGNOR TO STRAUSE GAS IRON CO., OF PHILADELPHIA, PENNSYLVANIA, A CORPORATION OF PENNSYLVANIA.

SELF-HEATING SADIRON.

1,399,813.

Specification of Letters Patent. Patented Dec. 13, 1921.

Application filed April 6, 1920. Serial No. 371,679.

To all whom it may concern:

Be it known that I, OTTO SPAHR, a citizen of the United States, and a resident of Philadelphia, county of Philadelphia, State 5 of Pennsylvania, have invented certain new and useful Improvements in Self-Heating Sadirons, of which the following is a specification.

My invention relates to self-heating sad
10 irons and has for its object to provide such
irons with an improved hinged or pivoted
cover construction and with an efficient and
simple locking means whereby said cover is
locked in its closed position to the body and
15 is readily unlocked therefrom when it is de-
sired to move said cover to its open pos-
ition. The details of my invention will be
fully set forth in the description hereinafter
and the features of novelty will be pointed
20 out in the appended claims.

In the accompanying drawings which illustrate an example of my invention without defining its limits, Figure 1 is a plan view of an iron embodying my invention; Fig. 2 is a side elevation thereof; Fig. 3 is a cross section on the line 3—3 of Fig. 1, and Figs. 4, 5, 6 and 7 are detail views illustrating variations of my invention.

As shown in the drawing the iron, which
30 may be of any conventional construction
common to self-heating irons, comprises a
hollow body 10 which in the example shown
is provided in its bottom with a channel 11
extending lengthwise of the iron and con-
35 nected with the atmosphere by means of
passages 12 extending transversely through
said bottom as shown in Fig. 3.

At its upper edge the body in the illustrated form is provided with end projections 13 and lugs 14 and 15 located intermediate thereof and opposite each other whereby openings 16 are formed through which the products of combustion may readily escape from the iron during use thereof.

45. A burner 17 of any suitable type is located within the body 10 and in the illustrated form is provided with oppositely and downwardly directed jet apertures 18 and may be continued exteriorly of the body in
50 the form of an upwardly inclined tube 19 provided in the customary manner with means for accommodating one end of the usual fuel tube whereby the burner is connected with a source of fuel supply in the
55 usual manner.

A cover 20 having the same general shape when looked at in plan as the body 10 when similarly viewed is provided for closing said body at the top. This cover 20 is movably connected with the iron for instance by being hinged on or pivotally connected with the lug 14 as shown at 21 in Fig. 3 and in this case is pivotally movable in a vertical plane to and from a closed position. 60

The said cover 20 is further provided with projections 22 on which a plate 23 preferably of metal possessing an inherent elasticity is positioned so as to be spaced from the cover whereby an air space 24 is formed between said plate and cover throughout substantially the entire area of the latter. The said plate 23 may be secured to the cover in any suitable manner as by screws 25 which may also serve to secure the handle 26 whereby the iron is manipulated to the 65 70 75

cover, washers or the like 27 being preferably located about said screws between said handle and said plate. In order that the cover 20 may be securely locked in its closed position I provide a latch or dog 28 which 80 in the illustrated example comprises an integral extension of the plate 23 and in any case is carried thereby as a component part subject to the inherent elasticity of said plate. The latch or dog 28 depends from the plate 23 at its periphery and projects 85

over and beyond the edge of the cover 20, said latch or dog having its free end inclined or curved inwardly to form a nose or projection 29 as shown in Fig. 3. The latch or dog 28 is arranged to coöperate with the lug 15 which projects upwardly from the

body 10 or with an equivalent device to firmly lock the cover in its closed position, said lug 15 being undercut or formed with an inclined surface 30 arranged to coöperate with the inclined nose 29 of the latch 28 to lock the cover 20 in its closed position. The

LOCK the cover 20 in its closed position. The engagement and disengagement of the described locking means is entirely automatic 10 in action and needs no individual or manual actuation of the locking elements when it is desired to open the cover.

desired to either lock the cover in its closed position or to open it. For instance, when the cover is closed as in Fig. 3 and it is desired to open it all that is necessary is to exert a force on the handle 26 tending to swing said cover 20 on the pivot 21 relatively to the body to an open position. This force will cause the inclined nose 29 of the 11

latch 28 to ride along the inclined surface 30 of the lug 15 and will consequently force the latch or dog 28 outwardly until the latter finally passes beyond the lug 15 and thus leaves the cover 20 free to be swung to its completely open position without difficulty. The outward swinging of the latch 28 will be resisted by its own resilient tension and by that of the plate 23 from which said latch depends so that the force must be sufficient to overcome this tension, it being of course understood that the body of the iron is held against movement in any suitable way during this operation, as by grasping the tube 19. As soon as the latch 28 has passed beyond the lug 15 the tension of said latch and of the plate 23 will be relieved and the latch or dog 28 will move inwardly. In swinging the cover on its pivot in the opposite direction to again close it, the nose 29 of the latch or dog 28 will engage the lug 15 and as a downward pressure is exerted upon the handle 26 will be forced outwardly thereby against its own tension and that of the plate 23 and as the closing movement of the cover is continued the nose 29 will finally be snapped into engagement with the lug surface 30 to again firmly lock the cover against movement relatively to the body. The tension exerted by the plate 23 plus that of the latch itself is sufficient to maintain the nose 29 firmly seated against the undercut surface 30 under ordinary conditions so that the iron may be freely lifted by the handle or otherwise manipulated during use without disengaging the locking means and without danger of causing an unintentional opening of the cover. The locking means itself needs no individual manipulation to lock or release the cover and is actuated entirely through the medium of the latter. It will be noted that the latch 28 does not contact with the edge of the cover over which it projects but is spaced therefrom when the cover is in its closed position. With this arrangement said latch 28 does not become excessively hot by conduction of heat from the cover, the plate 23 being located also at a distance from the cover and forming therewith an air space which insulates the tension means or more specifically the plate 23 against the heat radiating from the cover. The life of the latch 28 is thereby materially increased and it retains its inherent resiliency for a maximum period of time, this being true also of the plate 23. The inwardly inclined nose 29 of the latch 28 and the inclined surface 30 of the lug 15 coöperate to maintain the locking device in a condition of maximum efficiency at all times. That is to say wear of these coöperating surfaces is automatically taken up and compensated for because of the form thereof thus providing an efficient locking means throughout the life of the iron. The

locking arrangement because of its physical characteristics is economical to produce and does not require any special skill either in the manufacture or the setting up and manipulation. It will be understood that the cover 20 may be pivoted other than at the side of the iron and also that the type of locking arrangement herein shown and described may be used in combination with covers pivotally movable on the body in other ways than the one shown. 70

It will be further understood that the locking means may be combined with iron bodies of other shapes and constructions than the one shown without affecting the 80 efficiency of said locking means.

If desired the inwardly inclined nose 29 of the latch 28 may be replaced by projections 29^a and 29^b as shown in Figs. 4 to 7 inclusive in which case the lug 15 will be provided with proper coöoperating recesses arranged to receive said projections 29₂ and 29^b. 85

Various changes in the specific forms shown and described may be made within 90 the scope of the claims without departing from the spirit of my invention.

I claim:—

1. A self-heating sad iron comprising a body, a cover movably mounted thereon, a plate carried by said cover in spaced relation to the top surface thereof and constituting a heat-insulating device, a resilient locking member fixed upon and depending from said plate and deriving its resiliency at least in part therefrom and means on said body coöperating with said locking member to lock said cover in its closed position. 95

2. A self-heating sad iron comprising a body, a cover pivotally mounted thereon, a plate carried by said cover in spaced relation to its upper surface and having an inherent resiliency, a locking member fixed upon and depending from said plate over an edge of said cover, said locking member being maintained in and returned to its locking position by the resiliency of said plate, and a recessed locking lug on said body coöperating with said locking member to lock said cover in its closed position. 105

3. A self-heating sad iron comprising a body, a cover pivotally mounted thereon, a plate carried by said cover in spaced relation to its upper surface and having an inherent resiliency, a locking member comprising an integral extension of said plate and depending from the periphery thereof, said member having an inwardly turned nose at its free end, and a locking lug on said body having an undercut surface coöperating with the nose of said locking member to lock said cover in its closed position. 110

In testimony whereof I have hereunto set my hand.

OTTO SPAHR.
